UNITED STATES PATENT OFFICE.

FRANCIS A. VAUGHN, OF MILWAUKEE, WISCONSIN.

DESIGN FOR A LAMP POST AND BRACKET.

51,999.

Specification for Design.

Patented Apr. 30, 1918.

Application filed July 14, 1917. Serial No. 180,664. Term of patent 7 years.

To all whom it may concern:

Be it known that I, FRANCIS A. VAUGHN, a citizen of the United States, residing at Milwaukee, in the county of Milwaukee and State of Wisconsin, have invented a new, original, and ornamental Design for a Lamp Post and Bracket, of which the following is a description, reference being had to the accompanying drawing, forming part thereof.

Figure 1 is a side view of a lamp post and bracket showing my new design;

Fig. 2 is a top view thereof; and
Fig. 3 is a transverse sectional view taken on line 3—3 of Fig. 1.

I claim:

The ornamental design for a lamp post and bracket, as shown.

FRANCIS A. VAUGHN.

Witness:

MARIE GRAY.
